UNITED STATES PATENT OFFICE.

OSCAR A. DIETSCH, OF GLADSTONE, NORTH DAKOTA.

POULTRY-FOUNTAIN.

1,168,489.

Specification of Letters Patent. Patented Jan. 18, 1916.

Application filed November 5, 1914. Serial No. 870,354.

To all whom it may concern:

Be it known that I, OSCAR A. DIETSCH, a citizen of the United States, residing at Gladstone, in the county of Stark and State 5 of North Dakota, have invented certain new and useful Improvements in Poultry-Fountains; and I do hereby declare the following to be a full, clear, and exact description of the invention, such as will enable others 10 skilled in the art to which it appertains to make and use the same.

This invention relates to drinking fountains for poultry and more particularly to fountains having heating means thereto and 15 adapted for the use of young chickens.

The principal object of this invention is to provide a sanitary device whereby the lamp can be removed without the displacement of the fountain.

Another object of this invention is to provide a device whereby the drinking trough can be adjustably placed for young chickens or for chickens of considerable size.

Another object of this invention is to so 20 construct the fastening means for the trough that the same can be readily removed for the purpose of cleaning or repairing.

Other objects and advantages of this invention will be hereinafter more clearly set 25 forth in the specification and pointed out in the claim.

Similar characters of reference refer to similar parts throughout the specification and drawings, in which,

Figure 1 is a sectional elevation of this device in assembled formation. Fig. 2 is a 35 sectional view on the line 2, 2 of Fig. 1 looking in the direction of the arrow. Fig. 3 is a sectional view on the line 3, 3 of Fig. 2, 40 and Fig. 4 is a sectional view on the line 4, 4 of Fig. 2 and indicating the drinking trough in a lowered position.

In Fig. 1 of the drawings 1 is a container 45 for the fountain composed of any suitable material but preferably of circular sheet metal, having pivoted at 2 and 3 lifting handles 4 and 5 as plainly shown in said

figure. A conical shaped cover 6 is adapted to be seated upon the top edge 7 of the fountain and slightly projecting beyond the edge thereof as at 8, said covering having a centrally disposed aperture 9 at the top portion thereof and a filling opening 10 on one side thereof suitably closed by a cap 11. Suitable 50 integral flanges 12 and 13 are formed in the walls of the container adapted to seat

a door 14, said door having a knob 15 thereon for the purpose of readily lifting the door to uncover an opening in the wall of the container.

A false bottom 16 is formed in the lower portion of the container leaving the chamber 17 therebetween and the bottom 18 of the container, said false bottom having centrally disposed therein a casing 19 forming 65 a suitable receptacle for the lamp chimney and having rising therefrom a flue or chimney 20 which is adapted to penetrate the aperture 9 in the covering 6 and is retained from displacement therefrom by means of 70 an enlarged end 21 forming shoulders adapted to seat upon the cover 6 adjacent the edges of the opening 9.

A suitable lamp chimney 22 is mounted 75 in the receptacle 19 and has at oppositely disposed points thereon metallic springs 23 which are fastened at their lower ends to the outer wall of the chimney 22, and which are adapted to bind against the inner surface of the receptacle 19 to retain the chimney 22 80 in elevated position when the same has been lifted for the purpose of removing the lamp 24. The chimney 22 seats upon a suitable platform 25 having upturned flanged edges 85 26 fastened to the burner 27 of the lamp 24 but above the manipulating thumb key 28 thereof.

A shallow drinking trough 29 built preferably of metallic material is formed to match the contour of the container 1, the 90 outer wall 30 thereof being slightly sloped and the inner wall 31 being vertically disposed, and having a flange 32 depending therefrom. The flange 32 is adapted to seat over a suitable projection 33 having an enlarged head 34 so that the trough will not 95 become displaced therefrom and the wall 31 is adapted to seat beneath the end of a depending hook 35. In practice a suitable number of these supporting lugs and hooks 100 are formed to project from the outer wall of the container to suitably hold the trough in position.

A suitable spout 36 is adapted to project from the wall of the container 1 having a 105 downwardly curved mouth portion 37 adapted to feed liquid into the drinking trough.

For the convenience of young chickens or fowls a second series of projecting lugs 38 110 and projecting hooks 39 similar to the lugs 34 and 35 previously described, is formed

near the base portion of the container so that said drinking trough 29 can be lowered and fastened to these last mentioned lugs to allow the young chickens to drink therefrom. A flexible hose or tubing 40 is fastened over the mouth 37 of the spout 36 to direct the water into the trough in its lowered position as plainly indicated in dotted lines of Fig. 4.

5 In operation the spout 36 is first closed in any suitable manner when the chamber 41 is filled with drinking fluid through the vent 10 after which the cap 11 is seated thereover, the door 14 raised, the lamp chimney 22 pushed upwardly in its receptacle and the lamp 24 inserted in position, lighted, and the chimney lowered upon the platform 25, after which the door is closed. After the water becomes properly heated to remove the chill 10 therefrom, the closure (not shown) is removed from the spout 36 and the water allowed to fill the trough 29 for purposes of drinking, or if the trough is put in its lowered position, a tube 40 is attached to the spout 36 to direct the water into the lowered trough. If it is desired to remove the trough for purpose of cleaning or re-

15 20 25

pairing the spout 36 can be again closed for this purpose, thereby wasting but a minimum quantity of water.

Having thus described my invention, what I claim as new and desire to secure by Letters Patent is:—

A drinking fountain, comprising the combination with a container having a liquid chamber in the upper portion thereof, a heating chamber in the lower portion thereof, a division wall between said chamber and a hollow casing projecting upwardly from said partition, of a heating device, a 35 chimney for said heating device, and oppositely disposed spring members on the chimney adapted to engage the walls of the casing to hold said chimney suspended while the heating device is being removed or introduced into the heating chamber.

Having thus described my invention, what I claim as new and desire to secure by Letters Patent is:—

OSCAR A. DIETSCHÉ.
